UNITED STATES PATENT OFFICE.

FULGENCIO ARCHILA, OF BOGOTA, COLOMBIA.

WATERPROOF CASE.

Application filed April 23, 1926. Serial No. 104,213.

The present invention relates to water-proof cases, and aims to provide a novel and improved device of that kind intended especially for use by persons while in bathing, for carrying articles of personal use, such as cigarettes or tobacco and matches, coins, cosmetics, or the like, in order that the bather may carry such articles for convenient access when wanted without the articles getting wet while in the water.

The device is intended to be worn while in swimming or bathing for carrying upon the person such articles of personal use as desired, it being well known that bathers cannot usually carry such articles of personal use with them, and the articles must either be left in the possession of others, or in lockers or elsewhere where not easily available. With the present device, currency and coins may be carried for making purchases, and smokers may carry cigarettes or tobacco and matches. Women may also carry cosmetics, and the device may be used for carrying rings, or other valuables.

A further object of the invention is the provision of a waterproof case of novel and improved construction for obtaining a waterproof joint between the body and cover of the case.

Another object is the provision of such a device having novel means for clamping the body and cover of the case together.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein—

Figure 1 is a front view of the preferred embodiment of the invention.

Fig. 2 is a side elevation thereof.

Fig. 3 is a section on the line 3—3 of Fig. 2.

Fig. 4 is a longitudinal section of the cover of the case removed from the body.

Fig. 5 is a front view of a modified form of case.

Fig. 6 is a rear view thereof.

Fig. 7 is a section on the line 7—7 of Fig. 5.

Fig. 8 is a top view of the modified form of device.

Referring to Figs. 1, 2, 3 and 4, the case comprises the body 11 and cover 12 stamped from suitable sheet metal, and the case is of a convenient size and preferably rectangular in shape. The rim 13 of the body 11 has a bead 14, and the marginal portion of the cover is formed with a pressed rib 15 forming a groove at the inner side of the cover to accommodate the bead 14. A gasket 16, 60 constituting a sheet of normally flat soft rubber, is disposed across the inner side of the cover 12, and is carried by said cover, with the marginal portion of the gasket extending across the groove formed by the rib 15, 70 as seen in Fig. 4. A sheet metal plate 17 is disposed against the inner side of the gasket 16 and has inwardly extending flanges 18 to extend within the body 11 and overlap the rim 13 thereof, for guiding the cover and body together. As shown, rivets 19 are secured through the cover 12, gasket 16 and plate 17, to secure said parts together, although other means for securing them together may be used. The rib 15 of the cover 80 and marginal portion of the gasket 16 project beyond the plate 17, and when the body and cover of the case are moved together, the bead 14 will contact with the marginal portion of the gasket 16 and compress same 85 into the marginal groove of the cover, as seen in Fig. 3. By pressing the cover and body together tightly, the gasket 16 is bent partially around the bead 14 within the marginal groove of the cover at the inner and outer sides of the bead to provide a water

air tight seal or joint.

A holder or carrier is provided to receive the case and to clamp the body and cover thereof together, in order that the case may 95 be conveniently carried. This holder com-

prises the back 20, bottom 21 and front portion 22 stamped from a plate of suitable resilient sheet metal. The front portion 22 may have outstruck vertical ribs 23 to reinforce said front portion, and along the vertical side edges the front portion 22 has

pressed ribs 24 providing inner grooves to receive and accommodate the opposite side portions of the rib 15 of the cover 12 when the case is slid into the holder. The back 20 of the holder has a rearwardly pressed loop

25 to receive a strap, belt or band for attaching the holder to the arm, leg or body of the person using the device, in order that the de-

vice can be conveniently carried. The back 105 20 has forwardly extending wings or flanges

100

105

110

26 at its vertical side edges, extending across the edges of the front portion 22, whereby the holder comprises a receptacle or socket in which the case may be conveniently inserted.

In order to clamp the cover and body of the case tightly together within the holder, a transverse hinge rod 27 has its terminals engaged through the wings or flanges 26 in front of the front portion 22, and a cam lever 28, constituting a plate of suitable sheet metal, has the sleeve portions 29 embracing the hinge rod or pin 27, and a cam 30 to bear against the front portion 22 when the lever 28 is swung upwardly and rearwardly against the upper end portion of the front portion 22, as seen in Figs. 1, 2 and 3. The cam 30 will force the front portion 22 rearwardly, thereby clamping the case between the back 20 and front portion of the holder, to hold the body and cover of the case tightly together, as seen in Figs. 2 and 3. This will enable various articles to be carried in the case while in the water, without such articles becoming wet. By swinging the lever 28 forwardly and downwardly, the cam 30 is removed from the front portion 22, and said front portion of the holder may then spring forwardly, to release the case so that the case 30 may be readily lifted from the holder and the cover of the case removed. When the cover and body of the case are placed together, the case may be readily inserted downwardly into the holder, and the lever 28 swung upwardly to clamp the case within the holder.

In the embodiment of the invention shown in Figs. 5, 6, 7 and 8, the parts are all assembled in one unit, the cover 12' of the case being hingedly connected with the body 11' of the case, and the cam lever 28' also being connected to the body for clamping the cover against the bead 14' of the rim 13' of the body. The marginal portion of the cover 12' is curved or bent inwardly, as at 15', to conform to the bead 14', and the gasket 16' extending across the inner side of the cover has its marginal portion flexed by the portion 15' of the cover partly around the bead 14' when the cover and body are clamped together, as seen in Fig. 7, so as to provide a tight joint. A plate 17' is disposed against the inner side of the gasket 16' and has an inwardly struck loop or portion 18' to receive a packet of matches, as seen in Fig. 7. The cover 12', gasket 16' and plate 17' are secured together by rivets 19' as shown.

The lower end of the cover body are hingedly connected. Thus, a hinge leaf 20' is secured in any suitable manner to the lower end of the rim 13', and the lower end of the cover 12' has a portion 22' extending rearwardly and upwardly along a curved line and hingedly connected, as at 21', with the hinge leaf 20', thus permitting the cover

to be swung open forwardly and downwardly. The portion 22' is resilient so as to be capable of being sprung when the cover is closed, to hold the lower portion of the cover tightly against the lower portion of the bead 14'.

The cover 12', as shown, has the outstruck vertical ribs 23' to reinforce the cover, and the body 11' of the case has secured thereto a loop 25' to receive a belt, strap or band, in order to apply the case directly to the arm, leg or body of the user.

A double hinge joint is used between the cam lever 28' and the body 11' of the case. Thus, a hinge leaf or plate 26' is secured in any suitable manner to the upper portion of the rim 13', and a hinge link 27' connects the lever 28' and plate 26'. The link 27' has the parallel portions 31' and 32' and the curved resilient portions 34' connecting them. The sleeve portions 29' of the lever 28' embrace the portion 31' of the link, and the plate 26' has a sleeve 33' embracing the portion 32' of said link. The portions 34' of the link are adapted to straddle the upper ends of the cover 12' and gasket 16'.

When the cover is swung against the bead 14' of the body, the link 27' may be swung forwardly and downwardly to position the cam 30' in front of the upper portion of the cover 12', and the lever 28', constituting a plate of sheet metal, may then be swung downwardly and rearwardly so that the cam 30' will clamp the cover tightly against the body, to prevent the water entering the case. By swinging the lever 28' upwardly, it is released from the cover, and the lever 28' and link 27' may be raised, to permit the cover 12' to be swung open for access to the articles within the case. The portion 22' of the cover and portions 34' of the link 27' are resilient so that when the lever 28' is swung to clamp the cover against the body, the parts may yield, in addition to the yielding action of the gasket 16', to hold the cover and body tightly together. The upper or free end of the cover 12' has an outwardly curved lip 35' to receive the cam 30' when the lever 28' is positioned preparatory to swinging the lever for clamping the cover and body together. With this construction, the parts all remain assembled to prevent possible loss of any part of the device, while the device shown in the preferred form has the advantage of enabling the case to be removed from the holder.

The sheet metal parts of either device are preferably composed of such metal or are plated or otherwise finished as to prevent corrosion thereof, especially from the action of salt water.

Having thus described the invention, what is claimed as new is:—

1. A case comprising a body, a cover having a marginal groove to accommodate the

- rim of the body, a gasket of normally flat material secured to the inner surface of the cover and having a free edge portion extending across said groove to be forced into said groove and partly around the rim of the body at the inner and outer sides thereof, and means for clamping said cover and body together. 5
2. A case comprising a body having a rim provided with a bead, a cover having a marginal groove to accommodate said bead, a gasket of normally flat material secured to the inner surface of said cover and having a free marginal portion extending across said groove to be pressed into said groove and partly around said bead at the inner and outer sides thereof, and means for clamping the cover and body together. 10
3. A case comprising a body having a rim provided with a bead, a cover, a plate secured to the cover at the inner side thereof, a gasket clamped between said plate and cover and projecting beyond the plate to 15
- bear against said bead, the cover having a marginal groove beyond the plate to accommodate the bead and to receive the gasket with the gasket fitting partly around the bead at the inner and outer sides thereof, and means for clamping the cover and body together. 20
4. A case comprising a body whose rim is provided with a rounded bead, a cover, a gasket composed of normally flat material extending across the inner side of the cover, a plate secured to the cover at the inner side thereof, said gasket being clamped between said plate and cover and having an edge portion projecting beyond said plate to bear against said bead, the marginal portion of the cover being curved to conform to said bead and to flex said gasket partly around said bead, and means for clamping said cover and body together. 25 30 35 40
